UNITED STATES PATENT OFFICE.

FRANKLIN SMITH, OF DALLAS, IOWA.

TRAP.

1,062,126.

Specification of Letters Patent. Patented May 20, 1913.

Application filed August 3, 1912. Serial No. 713,127.

To all whom it may concern:

Be it known that I, FRANKLIN SMITH, a citizen of the United States, residing at Dallas, in the county of Marion and State 5 of Iowa, have invented certain new and useful Improvements in Traps, of which the following is a specification, reference being had to the accompanying drawings.

This invention relates to traps and has 10 for its object to provide a device of this character which can be utilized as an animal trap or a trap for flies, roaches or other insects.

The primary object of the invention re- 15 sides in the provision of a series of current receiving plates suitably insulated from each other and wired to the positive and negative poles of an electric circuit whereby, when the animal or insect treads upon 20 said plates, its body will be immediately charged with the electric current, resulting in instantaneous death.

Another object of the invention is to provide improved means for mounting and sup- 25 porting the electrically charged series of plates within a suitable frame whereby the plates of the positive and negative poles will be completely insulated or segregated from each other.

30 A still further object of the invention is to produce a trap of the above character which is efficient and reliable in use, may be inexpensively manufactured and will occupy a minimum of space.

35 With the above and other objects in view, the invention consists in the novel features of construction and the combination and ar- 40 arrangement of parts hereinafter more fully described, pointed out in the claim and shown in the accompanying drawings, in which—

Figure 1 is a perspective view of a trap embodying the present invention. Fig. 2 is a bottom plan view thereof and Fig. 3 is 45 a longitudinal section.

Referring in detail to the drawing, 5 designates a rectangular frame in one end of which an outwardly opening hinged door 6 is ar- 50 ranged. Upon the side walls of the frame 5, the inclined glass plates 7 are secured in any preferred manner, said plates extending from the upper end of the rear wall of the frame 5 to the lower edge of the swinging hinged door 6. Upon the upper edges of these glass 55 plates 7, a metal plate 8 is mounted and secured, said glass plates insulating the same

from the metallic walls of the frame 5. From the forward edge of the plate 8 to the front edges of the side walls of the frame, the upper edges of the glass plates 60 7 are obtusely inclined with relation to the remaining upper edge portions thereof as indicated at 11. To the inner surface of the glass plates 7 contiguous to these inclined edges 11, the metal bars 12 and 13 are se- 65 cured. The metal bar or strip 12 is connected to the positive pole of an electric circuit by means of the wire 14, while the bar 13 is connected to the negative pole of the circuit by means of the wire 15. Between 70 the metal bars 12 and 13, a plurality of parallel metal plates 16 are arranged, said plates being insulated from each other by means of rubber or suitable fiber indicated at 17, thus forming a grid, the surface of 75 which is disposed in a plane which is inclined obtusely with relation to the upper surface of the metal plate 8. It will be ob- 80 served that the opposite ends of alternate plates 16 are in contact with the bars 12 and 13 respectively so that every other one of the plates 16 is charged with the negative current while the remaining plates receive the positive current. Thus when the animal or insect treads upon these charged plates, 85 the circuit will be closed and the current passed through its body. After the animal or insect has thus been killed, its body will slide or roll down the inclined surface formed by the plates 16 and move out- 90 wardly under the swinging door 6. If de- 95 sired, a hook 18 may be secured to the trans- verse frame bar to which the upper edge of the door 6 is hinged to receive a suitable bait to attract the animals or insects. The positive and negative wires 14 and 15 are connected to a threaded plug (not shown) which is adapted to be screwed into the lamp socket of an electric lighting circuit.

From the foregoing it is thought that the 100 construction and manner of operation of my improved trap will be clearly understood. It will, of course, be appreciated that the same may be made in various sizes and the relative angular disposition of the 105 segmental grind and the negative current re- ceiving plate varied as circumstances may require. Owing to the fact that but few ele- 110 ments are employed in the construction of the device it will be appreciated that the same can be manufactured at small cost and is also extremely durable in use. The trap

is also highly efficient and reliable and may be successfully employed in the trapping and killing of various species of animals and insects.

5 While I have shown the preferred form and arrangement of the various parts, it will be understood that the invention is susceptible of considerable modification without departing from the essential features or 10 sacrificing any of the advantages thereof.

What I claim is:—

A trap comprising a frame having a swinging door mounted in one end, glass plates arranged at an inclination upon the 15 inner faces of the side walls of the frame and terminated at one of their ends at the lower edge of the swinging door, a metal

plate mounted upon said glass plates, a grid mounted upon said glass plates and disposed at an obtuse inclination to said plate, 20 said grid consisting of parallel side bars and a plurality of parallel plates arranged between said side bars, the ends of the alternate plates contacting with the respective side bars, insulating strips disposed between 25 the adjacent plates, and positive and negative current conducting wires connected to said metallic side bars.

In testimony whereof I hereunto affix my signature in the presence of two witnesses. 30

FRANKLIN SMITH.
